UNITED STATES PATENT OFFICE.

DANIEL T. MCNIEL AND JOHN B. CARTER, OF KOKOMO, INDIANA.

VENTILATOR.

SPECIFICATION forming part of Letters Patent No. 340,806, dated April 27, 1886.

Application filed February 25, 1886. Serial No. 193,219. (No model.)

To all whom it may concern:

Be it known that we, DANIEL T. MCNIEL and JOHN B. CARTER, of Kokomo, in the county of Howard and State of Indiana, have 5 invented certain new and useful Improvements in Ventilation of Houses; and we do hereby declare the following to be a full, clear, and exact description of the invention, such as will enable others skilled in the art to which it 10 pertains to make and use it, reference being had to the accompanying drawings, which form part of this specification.

Our invention relates to an improvement in the ventilation of buildings; and it consists 15 in a metallic flue which is provided with registers for ventilating the rooms, guards placed in the flue, and a stove-pipe which is placed inside of the flue and connected with the various rooms, all of which will be more 20 fully described hereinafter.

The object of our invention is to provide a 25 double flue which is made wholly of metal, and which is connected with each of the rooms, one above the other, whereby each room can be ventilated thoroughly without the slightest danger of any of the foul air or gases from one of the lower rooms passing up through the 30 registers in any of the rooms above.

In the accompanying drawings, Figure 1 35 represents a vertical section of a metallic register embodying our invention. Fig. 2 shows a modification.

A represents a metallic flue, which is placed 40 inside of the chimney or in the wall, as may be desired. Through the inner side of this flue in each room there is made an opening, 45 B, for ventilation, and each one of these openings is controlled by a register, C, of any suitable construction. These openings, which are made near the floor in each room, enable 50 all the foul air and gases which may have settled near the floor to be drawn off through the flue at will by opening or closing the register. In order to prevent the foul air and 55 gases which pass into the flue from one of the lower chambers from passing up through the register into one of the rooms above, a guard, G, is placed in the flue below each opening B, so as to conduct the gases upward and beyond 60 the openings, and thus prevent them from passing into one of the rooms above, as they

would be liable to do if the guard G were not used. This opening B can also be used to admit fresh air into the rooms when the air is cool enough to descend through the flue. 55 Placed in the center of this flue is a vertical stove-pipe, H, which is connected by the small pipes I with each one of the rooms past which the flue A passes. This pipe H is made perfectly tight so far as the flue A is concerned, 60 and hence no smoke or gases arising from the products of combustion will interfere with the air in the flue, and thus prevent a perfect ventilation. During the winter, or when a 65 stove is in operation and connected with this pipe H, the products of combustion passing through this pipe H will heat the air in the flue, and thus cause an upward draft through the flue, which will ventilate thoroughly each 70 one of the rooms in which the register is open.

From the construction above described it will be seen that a double flue constructed entirely from metal is used, and one which can be produced much more cheaply than one made 75 from bricks alone, or from brick and tiles, which have heretofore been used for this purpose. After the dimensions are known the flue can be readily made and placed into position ready for use, and at comparatively 80 very little expense. This flue carries off not only products of combustion, but ventilates each room, and that without allowing the foul air and gases of one room from passing into the room or rooms above it. 85

Where the flue and ventilator are to extend directly up through a ceiling, the flue and stove-pipe H will be constructed as shown in Fig. 2. In this case the stove-pipe H will be placed in the center of the flue, and the flue- 90 pipe will be supported by the perforated plate P, which is secured in position in any suitable manner. Through this plate are made suitable ventilating-openings, which are controlled by the valves or valve Q. These valves may 95 open either upward or downward, and may be held in any desired position by means of counter-weights or any devices which will answer for this purpose.

We do not restrict our invention to any 100 particular devices for either operating the valves or holding them in any desired position.

We are aware that a stove-pipe flue has been placed inside of a ventilating-pipe, and that the ventilating-pipe has been provided with means for ventilating the rooms with which it is connected, and this we disclaim.

Having thus described our invention, we claim—

The flue A, provided with the openings B, the registers C, and the guards G, with the pipes

H, I, combined and arranged substantially as so described.

In testimony whereof we affix our signatures in presence of two witnesses.

DANIEL T. McNIEL.

JOHN B. CARTER.
